UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

DISTILLING BITUMEN

Application filed December 18, 1925, Serial No. 76,170. Renewed October 7, 1929.

This invention relates to a process of distilling bitumens, and refers more particularly to a process of removing from bituminous materials of a solid or semi-solid nature, as for example, coal tars, natural or artificial asphalts, shale, peat or the like, the hydrocarbonaceous constituents contained therein.

Another feature of this invention is to produce a very large quantity of fixed or incondensable gases suitable for industrial purposes.

The invention is characterized by subjecting such bituminous material to the action of highly heated petroleum oil, while at the same time subjecting the material to the action of air, which air serves to promote direct combustion in the chamber containing the bituminous materials.

In order to understand the process, I have shown the accompanying drawing, in which the single figure is a somewhat diagrammatic side elevational view, partly in vertical section, showing an apparatus suitable for practicing the process.

Referring to the drawing, 1 represents a furnace in which is mounted a heating coil 2. The petroleum oil is fed to the inlet side of the coil through the feed line 3 having a throttle valve 4 connected to feed line 5 leading to any suitable source of supply, as for instance, a charging tank containing petroleum oil or fuel oil. The oil passes from the coil through the transfer line 6 controlled by the throttle valve 7 into the treating chamber 8, which chamber 8 is provided with manholes 9 and 10, liquid drawoff 11 controlled by throttle valve 12, and is interiorly insulated as shown at 13. The vapors pass out of the chamber 8 through the vapor line 14 controlled by the throttle valve 15 into the lower part of the dephlegmator 16. The reflux condensate may pass out through the pipe 17 and by means of pump 18 to the feed line 3. The pump 18 may be by-passed through the by-pass 19 by suitably controlling the valves 20,

21 and 22. The vapors pass out of the system through the pipe 23 controlled by the valve 25, to the water condenser 24 and to the receiver 26, which receiver is provided with gas outlet pipe 27 having throttle valve 28 and liquid drawoff pipe 29 having a throttle valve 30. A vacuum pump 27' is connected to the gas outlet pipe 27 whereby a vacuum may be maintained on more or less of the system in the manner hereinafter described.

As a feature of the invention, air is introduced directly into the material in the chamber 8 by means of air pipe 31, controlled by throttle valve 32, to which pipe is connected the air pump 33. The upper end of the pipe is provided with a spaced cover 34, the arrangement being such as to permit the air to readily enter the chamber 8 but prevent the oil constituents from dropping back into and choking up the pipe. The purpose of introducing air into the chamber is to cause internal combustion of part of the bituminous and petroleum material. The action of the air is not only to promote combustion and thus facilitate cracking, but more particularly to facilitate cracking towards the gas stage, and produce substantial quantities of fixed gases.

The chamber 8 is charged with bituminous material of any suitable character such as has been heretofore mentioned, and the petroleum oil as for example, fuel oil, is pumped through the coil 2 where it is heated to a transfer temperature in the line 6 of say 800° F. more or less. This hot oil passes to the chamber 8 where it comes into intimate contact with the bituminous material therein contained, and dissolves out some of the hydrocarbonaceous constituents thereof, and likewise distills such constituents. At the same time, air is introduced in regulated quantities, which air combines with the hot petroleum oil and hot hydrocarbonaceous constituents of the bitumen to cause combustion, with the result that certain portions

of the petroleum and bitumen are burned. This of course, raises the temperature, and thus tends to facilitate cracking, particularly cracking to the gas stage. The action is such that the material in the chamber 8 may be heated to a temperature of say from 1000° to 1200° F. more or less.

As heretofore stated, the chamber 8 is internally insulated so as to withstand the temperature conditions to which it is subjected.

The liquid material may be drawn off through the pipe 11 controlled by the valve 12, and the vapors pass out through the pipe 14 into the dephlegmator 16 where the heavier portions are condensed, and may be returned to the system for further treatment, through the pump 18, or by-pass 19, or if desired, may be drawn off from the system through the line 20' controlled by throttle valve 21'.

In carrying out the process, a pressure of say 500 pounds more or less, may be maintained on the oil in the coil 2, while by suitably controlling the valve 7, a vacuum of from 15 to 28 inches may be maintained on the chamber 8 and the balance of the system. By means of this vacuum, the oil passing the coil 2 will have a tendency to very largely flash in the vapor line, thus increasing the tendency of the petroleum also to be cracked into substantial quantities of incondensable gas, particularly if the temperature in the chamber 8 is maintained relatively high, say from 1000° to 1500° F., and moreover, caused to travel a relatively long distance through the chamber 8. While I have shown this chamber 8 as vertical, it might be horizontal.

By suitably controlling the vacuum and air pump, the amount of vacuum interposed may be regulated at will. If desired, open ended pipes may be supplied for the air pump.

It is obvious that the temperatures and pressures set forth may be varied, within wide limits.

I claim as my invention:

1. A process for distilling bituminous materials of a solid or semi-solid nature which consists in charging a mass of the bituminous materials into an enlarged zone, maintaining a zone of combustion in said mass, in separately heating a supply of hydrocarbon liquids to a temperature of substantially 800 degrees F. under a super-atmospheric pressure, admitting the liquid hydrocarbons while at such temperature into the zone of combustion in said mass of bituminous material, continuously supplying regulated quantities of air to the zone of combustion in said mass of bituminous material to effect a controlled combustion thereof, in maintaining a sub-atmospheric pressure on said mass of

bituminous material and in recovering the vaporous constituents evolved therefrom.

2. A process for distilling bituminous materials of a solid or semi-solid nature which consists in charging a mass of the bituminous materials into an enlarged zone, maintaining a zone of combustion in said mass, in separately heating a supply of hydrocarbon liquids to a temperature of substantially 800 degrees F. under a super-atmospheric pressure, admitting the liquid hydrocarbons while at such temperature into the zone of combustion in said mass of bituminous material, continuously supplying regulated quantities of air to the zone of combustion in said mass of bituminous material to effect a controlled combustion thereof, in maintaining a sub-atmospheric pressure on said mass of bituminous material, taking off vaporous constituents evolved from the hydrocarbon liquids and bituminous material in said enlarged zone, subjecting such vapors to a primary cooling to separate the higher boiling point fractions therefrom, and uniting heavier fractions separated from such vaporous constituents as the result of said primary cooling with the hydrocarbon liquids undergoing treatment.

3. In the art of recovering values from hydrocarbon sources, the process which comprises charging a chamber with solid hydrocarbon-bearing material, maintaining a zone of combustion within the material in the chamber, separately heating a hydrocarbon liquid under pressure to cracking temperature and subsequently introducing the same at cracking temperature and without separation of vapors therefrom into said zone of combustion in said solid material in said chamber, injecting regulated quantities of air into said zone of combustion simultaneously with the introduction of the heated hydrocarbon liquid thereto to effect partial combustion of the solids and fluids therein and to produce a substantial quantity of gas, removing vapors and gases from said chamber, and separating the vapors from the gases by condensation.

4. A process as defined in claim 3 further characterized in that said chamber is maintained under sub-atmospheric pressure.

5. In the art of recovering values from hydrocarbon sources, the process which comprises charging a chamber with solid hydrocarbon-bearing material, maintaining a zone of combustion within the material in the chamber, separately heating a hydrocarbon liquid under pressure to cracking temperature and subsequently introducing the same at cracking temperature and without separation of vapors therefrom into said zone of combustion in said solid material in said chamber, injecting regulated quantities of air into said zone of combustion simultaneously with the introduction of the heated hydro-

carbon liquid thereto to effect partial combustion of the solids and fluids therein and to produce a substantial quantity of gas, removing vapors and gases from said chamber and subjecting the same to dephlegmation to condense heavier fractions thereof as reflux condensate, utilizing said reflux condensate as at least a part of said hydrocarbon liquid, and separately collecting the gases produced in said chamber.

GUSTAV EGLOFF.
